UNITED STATES PATENT OFFICE.

DAVID CONLAN, JR., OF BROOKLYN, NEW YORK.

DRY CELL.

1,193,764.

Specification of Letters Patent. Patented Aug. 8, 1916.

Application filed November 16, 1915. Serial No. 61,753.

To all whom it may concern:

Be it known that I, DAVID CONLAN, Jr., a citizen of the United States of America, residing at Brooklyn, New York, have invented a new and useful Dry Cell, of which the following is a specification.

The primary object of this invention is to eliminate the need for separate connectors which have heretofore been required in connecting up dry cells in sets or batteries.

Another object is to construct a dry cell which may be used singly and be connected with the two-circuit wires in the usual way and which can when so desired be as readily connected with the adjacent cell of a battery.

In the accomplishment of these objects I employ a connector which is rigidly secured at one end to one element of the cell, as for instance, the zinc container of the usual dry cell, which when not in use is out of the way so as not to interfere with the usual handling of the cell and which can be used to provide a good electrical connection between the cell and an adjoining cell or other element. Preferably this connector is in the form of a relatively flat flexible strip which when not in use will lie close to the container and be covered by the card-board or other insulating casing with which dry cells are usually supplied.

A special feature of the invention is the utilization of one of the binding post terminals with which dry cells are usually provided as a means for securing the connector to the cell.

Various other features and details of structure will appear as the specification proceeds and will become clear from consideration of the accompanying drawing which illustrates the invention embodied in a practical and preferred form.

In the drawing:—Figure 1 is a perspective view of a dry cell embodying the invention shown coupled to an adjoining cell by means of the connection carried thereby. Fig. 2 is a view of the cell minus the casing illustrating a method of securing a connecting strip by means of one of the binding terminals. Fig. 3, is a sectional view of the complete cell showing the connecting strip in the position it occupies when not in use, between the container and the casing. Fig. 4, is a view showing the protective insulating casing partly withdrawn to

expose the connection strip. Fig. 5, is a view showing the connecting strip withdrawn ready for use and the casing slipped back into its protecting position, the casing and the container appearing here in section.

The dry cell illustrated consists of a metallic receiver 7 of zinc or the like containing active material 8 in a more or less wet or plastic state and a rod 9 of carbon or other suitable material, constituting the other pole of the cell.

The carbon element is shown provided with a suitable binding post terminal 10 and the zinc container element with a suitable binding post terminal 11. The zinc terminal may be in the form of a screw post 12, slotted at its lower end as indicated at 13 to pass down over the edge of the container.

15 indicates the connector carried by the cell and secured rigidly at one end to one of the cell elements, in this particular instance to the zinc container, by being engaged beneath the slotted terminal post as the same is engaged over the upper edge of the container as indicated in Figs. 2 and 3. After 80 the end of the connector has thus been secured in place, the joint may be made permanent by the use of solder substantially as is indicated at 16.

The connector 15 is made of relatively flexible material having good electrical conductivity and I prefer to employ at the present time for this purpose a relatively narrow strip of close mesh copper or brass wire gauze. This material is inexpensive, 90 forms a good conductor, is extremely flexible and can be flexed a great number of times without breaking and in addition to all this is flat so that it will lie close against the metallic container and fit in between the 95 container and the insulating casing 17 which usually surrounds and incloses the cell.

The connecting strip is provided at its free end with means adapting it to be connected with the terminal portion of an adjoining cell, in the present instance by providing it with an opening 18 to fit over a binding post. This terminal engaging end of the connecting strip is also in this case reinforced by bending the end of the strip 105 back upon itself as indicated at 19, said reversely bent portion 19 having an opening 20 therein corresponding to the opening 18. In addition to the reinforcing effect thus obtained, this reversely bent portion pro- 110

vides a spring terminal which is compressed beneath the binding screw or other clamping device insuring a good electrical contact and also serving in a way as a nut lock to prevent unscrewing or loosening of the binding device.

The intermediate portion of the connecting strip may be insulated as indicated at 21 in Fig. 1 as by coating or impregnating 10 the gauze strip with an insulating compound of suitable character or by engaging a wrapper or covering of paper or other insulating medium over the intermediate portion of the strip as indicated at 22 in Fig. 5. This 15 insulation of the intermediate portion of the strip prevents short circuiting in case the strip should be forced down into engagement with the rim of the cell.

In the form of the invention illustrated 20 the cell is shipped with the connecting strip in place between the metallic casing and the insulating housing as indicated in Fig. 3, the strip in this way being concealed and protected and adding no bulk or appreciable 25 weight to the cell. When the cell thus constructed is to be connected in a battery the casing is partly or wholly withdrawn so as to expose the strip or a portion of the strip as indicated in Fig. 4, the strip is drawn 30 outward and the casing is then replaced as indicated in Fig. 5 with the connecting strip on the outside. If at any time the connecting strip is not needed it may be replaced inside the protective casing. With the wire 35 gauze form of connector strip, the flexibility is such as to permit the strip being bent back and forth and replaced and withdrawn any number of times without breaking or injuring the strip.

40 From the foregoing it will be apparent that my invention provides a practical and simple inexpensive form of connector, constituting an integral part of the cell which

cannot be mislaid or displaced and which is ready for instant use at any time. 45

What I claim is:—

1. In a dry cell, the combination with a metallic container constituting one element of the cell and an insulating casing inclosing 50 said container and readily removable therefrom, of a relatively flat flexible metallic strip secured to said container, normally lying flat against the container between the container and the insulating casing surrounding it and adapted to be exposed by 55 removal of the casing and be thereupon withdrawn to form a connector for engagement with another cell and a binding post connected to the metallic container and securing the connecting strip thereto. 60

2. In combination, a dry cell including a metallic container constituting one element of the cell, active material in said container, a second element in said active material and binding posts carried by the respective elements and a relatively flexible connecting strip permanently secured at one end to one of said cell elements and provided at its opposite free end with means adapting it to be engaged with the binding device of an 70 adjoining cell or other member.

3. In combination, a dry cell including a metallic container constituting one element of the cell, active material in said container, a second element in said active material and 75 binding posts carried by the respective elements and a relatively flat flexible metallic strip secured at one end to the container element of the cell provided at its opposite free end with an opening adapted for engagement over a binding device and a casing of insulating material engaged over the container element and normally covering the flat connecting strip secured thereto. 80

DAVID CONLAN, JR.
